DESIGN FOR A TOY TRUCK

George Lerner and Samuel Gilbert,
Los Angeles, Calif.

Application February 21, 1945, Serial No. 118,067

Term of patent 3½ years

(Cl. D34—15)

To all whom it may concern:

Be it known that we, George Lerner and Samuel Gilbert, citizens of the United States, residing at Los Angeles, in the county of Los Angeles and State of California, have invented a new, original, and ornamental Design for a Toy Truck, of which the following is a specification, reference being had to the accompanying drawing, forming part thereof.

truck showing our new design, the opposite side presenting substantially the same appearance as the side shown; and Figure 2 is a plan view of the moving screen.

We claim:

The ornamental design for a toy truck, substantially as shown and described.

GEORGE LERNER.
SAMUEL GILBERT.
